UNITED STATES PATENT OFFICE.

PATRICK CAHILL, OF LEEDS, MASSACHUSETTS, ASSIGNOR TO GEORGE P. WARNER, OF SAME PLACE.

IMPROVEMENT IN MACHINES FOR POLISHING BUTTONS.

Specification forming part of Letters Patent No. 174,896, dated March 21, 1876; application filed February 25, 1876.

To all whom it may concern:

Be it known that I, PATRICK CAHILL, of Leeds, in the county of Hampshire and State of Massachusetts, have invented certain new and useful Improvements pertaining to a Button-Polishing Machine, of which the following is a specification, reference being had to the accompanying drawings, where—

Figure 1 is a side view. Fig. 2 is a front view. Fig. 3 is a top view. Fig. 4 is a partial section on plane $x\ x$. Fig. 5 is a top view from plane $x'\ x'$. Fig. 6 is a detail view in central vertical section of shaft y , (hereinafter referred to,) modified for certain purposes.

This machine is intended for polishing buttons of vegetable ivory or other proper material.

The letter a denotes the table of the machine; $b\ b$, uprights; c , main shaft; d , pitman from crank on main shaft giving vertical reciprocation to cross-head e , bearing the punch-die f .

Pin h on disk g gives reciprocation to pivoted lever i , and, through the medium of connecting-rod k , to slide l , on which is pivoted the pawl m , pressed forward by spring n against the periphery of carrier-plate o —which rotates on pin p —taking into notches r , so as to give step-by-step rotation to the carrier-plate, which rests on plate s , and contains the button-sockets t , into which the button-blanks are fed, and, after being operated on, escape through the trough or pipe u .

The carrier-plate is held locked at proper intervals to allow the buttons to be operated on by the pawl v , pressed forward by spring w . This pawl is unlocked from its hold on the carrier-plate at proper intervals, to allow the step-by-step rotation, by the shoulder l' on slide l .

Under the table is hung the vertical shaft y rotating from shaft z through the medium of gears $a'\ b'$. The lower bearing or step c' for shaft y is upon plate d' , underneath which is spring e' , the purpose and office of which is this: The buttons while being polished rest upon the top of shaft y , under

pressure of die f . These buttons vary in thickness somewhat, even when cut at first to uniformity, on account of unequal expansion or contraction in subsequent drying, and when a thick button comes under the polishing operation the spring e' allows shaft y to give, and, to prevent breaking the button or straining the machine, the strength of the resistance of spring e' is regulated by nuts j' on bolts g' . Nuts h' hold plates d' to proper elevation.

Shaft y rotates continuously, and as the carrier-plate brings the buttons one by one under operation over and upon the end of this shaft, the carrier-plate there stops for a proper interval, the punch-die f descends and presses upon the button, and the upper end of shaft y being roughened the button revolves with it, and thereby the upper face of the button is polished by rotation against the smooth face of the punch-die. The punch-die then ascends, leaving the button in its socket, and the button moves on.

If the button chance to adhere to the punch-die, it is detached by means as follows: Inside the punch-die is the extractor-rod i' pressed upward by spring j^1 . As the punch-die commences to ascend, the vertical arm of the pivoted bell-crank lever j^2 —carried on the cross-head—strikes against bar k' , pushing the lateral arm downward, and thereby causing the extractor to project from the punch-die, and so detach the adhering button.

I have found that buttons with full back and thin edge and flat, or nearly flat, top will not always readily move out of the die which is on the top of shaft y , and when they do not they are apt to be caught and broken by the rotating carrier-block. To obviate this difficulty with such buttons, I construct the top of shaft y as shown in central section in Fig. 6, where y denotes the shaft in which is set the extractor m^1 , pressed upward by spring n' , kept from rising too high by the cross-pin o' running through the mortise p' , and from falling too low by the shoulder m^2 abutting on the shoulder y' .

I claim as my invention—

1. In combination, the non-rotating die f ,

the rotating die y , and the spring e' , substantially as described, and for the purpose set forth.

2. In combination, the reciprocating die f , extractor i , and operating lever j' , all substantially as described, and for the purpose set forth.

3. In combination, the rotating carrier-

plate o , rotating shaft y , and extractor m^1 , all substantially as described, and for the purpose set forth.

PATRICK CAHILL.
